UNITED STATES PATENT OFFICE.

RUSSELL PERKINS AMBLER, OF DE FUNIAK SPRINGS, FLORIDA.

BURNER.

SPECIFICATION forming part of Letters Patent No. 396,798, dated January 29, 1889.

Application filed October 20, 1887. Serial No. 252,927. (No model.)

To all whom it may concern:

Be it known that I, RUSSELL PERKINS AMBLER, a citizen of the United States, residing at De Funak Springs, in the county of Walton and State of Florida, have invented a new and useful Improvement in Burners, of which the following is a specification.

My invention relates to an improvement in burners for kerosene-oil for lighting and heating purposes; and it consists in the peculiar construction and combination of devices, that will be more fully set forth hereinafter, and particularly pointed out in the claims.

In the accompanying drawings, Figure 1 is a vertical longitudinal sectional view of a burner embodying my improvements. Fig. 2 is a vertical transverse sectional view of the same, taken on the line $x-x$ of Fig. 1. Fig. 3 is a detached perspective view of a portion of the wick-casing, and showing the wick and the filtering and heat-radiating medium.

A represents the base of the burner, which is provided with a longitudinal central channel, B, that communicates at one end with a pipe, C, which pipe extends to a reservoir, (not shown,) and is arranged in an elevated position, and is adapted to contain kerosene-oil. The base A is supported upon suitable legs or feet, E, and is provided with a central cross-bar, F, arranged at a suitable distance below the bottom of the base.

G represents a vertical case or shell, of suitable length and width, which extends upward from the base and is provided at its upper edges with a horizontal plate, H, which extends outward beyond the sides of the case or shell G, and is provided with a central longitudinal opening, I, of suitable length and width. On this plate H is supported a chimney, K.

L represents a vertically-movable slide or gland, which is arranged on the inner side of the case or shell G, and is similar thereto in shape, but enough smaller than the shell or case to leave an air-channel, M, between the opposing sides of the gland and the case. The upper end of the gland is closed and is provided with a longitudinal opening, N, which is considerably smaller than the opening I. The sides of this opening N form plates or flexures O, that extend inward from the sides of the gland.

P represents the wick-tube, which corresponds in general shape to the gland or slide, but is enough smaller than the latter to fit inside of the same and leave a space or channel, R, between the opposing sides of the wick-tube and the gland.

S represents vertical openings which extend entirely through the base A and communicate with the lower ends of the spaces or channels M and R.

T represents a series of vertical openings which are made in the upper portion of the base and connect the channel B with the lower end of the wick-tube. The latter is firmly secured on the center of the base.

U represents a plate which is arranged under the bottom of the base, and is supported above the cross-bar F by means of a vertical screw, V, which is swiveled in the bar F and has its upper threaded portion engaging the plate U.

W represents a series of studs which are wedge-shaped in form, extend from the upper side of the plate U, pass through the openings S into the base, and bear against the lower edges of the slide or gland L.

From the foregoing description it will be readily understood that by turning the screw V the plate U may be raised or lowered, so as to cause the wedge-shaped studs W to raise or lower the gland, and thereby raise or lower the flange plates or flexures O above the upper end of the wick-tube.

X represents a wick-envelope, which is made of wire-gauze and is adapted to fit in the wick-tube. The height of this wick-envelope is somewhat in excess of the height of the wick-tube, so that the upper end of the wick-envelope will extend through the opening N at the upper end of the gland.

Y represents the wick, which extends through the wick-envelope to within a suitable distance of the upper end thereof or to about the height of the upper end of the wick-tube. That portion of the wick-envelope which extends above the wick forms a supplemental chamber which is filled with a mixture, Z, of iron filings and powdered charcoal or other suitable heat-conducting and other filtering materials.

The operation of my invention is as follows: The oil is forced from the reservoir through

the pipe C and the channel B and through the openings T to the lower end of the wick by hydrostatic pressure, and the oil is absorbed by the wick and carried upward 5 through the wick-tube by capillary attraction. From the upper end of the wick the oil passes through the filling Z. A current of air passes upward through the space or channel R between the wick-tube and the 10 gland to the base of the supplementary wick-envelope, and another current of air passes upward through the space or channel M between the gland and the case G to the under side of the plate H. By turning the screw V in 15 one direction, so as to raise the plate U, the wedge-shaped studs W elevate the gland or slide L and close the openings S, thus shutting off the quantity of air supplied to the wick-chamber. By lowering the plate U the studs W 20 are withdrawn from the openings S and the gland or slide L, thereby allowing the flame to be supplied with air. By this means the flame may be controlled, as will be readily understood, without raising or lowering the 25 wick. When the oil in the supplemental chamber is ignited, heat is imparted to the iron filings in the supplemental chamber, and thereby the globules of oil in the supplemental chamber are converted into vapor before reaching the flame, and consequently the 30 combustion of every particle of the oil is caused and the flame burns clearly and without smoke, even though the chimney K be removed. Inasmuch as the material in the 35 supplemental chamber is interposed between the base of the flame and the upper end of the wick, the latter is prevented from being charred and consumed, and consequently is caused to last for an indefinite length of time. 40 Having thus described my invention, I claim—

1. The combination, in a burner for kerosene-oil, of the base A, having the case G, the vertically-movable gland arranged in the case 45 and having its upper end closed and provided with an opening, N, the wick-tube arranged in

the said gland and communicating with the oil-reservoir, channels or spaces M and R being formed between the opposing sides of the case G, the gland, and the wick-tube, the said 50 channels communicating with the outer air, substantially as described.

2. The combination, in a burner for kerosene-oil, of the base A, having the case G, provided at its upper end with the plate H, having the opening I, the vertically-movable gland arranged in the said case and having its upper end closed and provided with the opening N, the wick-tube arranged in the gland and communicating with the oil-reservoir, channels 55 or spaces M R being formed between the opposing sides of the case, the gland, and the wick-tube, and said channels communicating with the outer air, substantially as described.

3. The combination, in a burner for kerosene-oil, of the base-plate provided with the openings S, and having the channel B communicating with the reservoir, the wick-tube arranged on the base and communicating at its lower end with the channel B, the vertically- 60 movable gland L, arranged around the wick-tube and having its upper end closed and provided with an opening, N, above the upper end of the wick-tube, the casing G, supported on the base and arranged around the 65 gland, the said casing having the plate H at its upper end provided with the opening I, for the purpose set forth, channels M and R being formed between the opposing sides of the casing, the gland, and the wick-tube, and communicating with the openings S, and the vertically-adjustable plate U, having the wedge-shaped studs W projecting upward through the openings S and supporting the gland, substantially as described.

In testimony that I claim the foregoing as my own I have hereto affixed my signature in presence of two witnesses.

RUSSELL PERKINS AMBLER.
